CLAIM

The ornamental design for a scooter, as shown and described.

DESCRIPTION

FIG. 1 is a top-rear-left side perspective view of a scooter embodying my new design;

FIG. 2 is a bottom-front-right side perspective view thereof;

FIG. 3 is a left side elevation view thereof;

FIG. 4 is a right side elevation view thereof;

FIG. 5 is a front elevation view thereof;

FIG. 6 is a rear view thereof;

FIG. 7 is a top plan view thereof; and,

FIG. 8 is a bottom plan view thereof.

The broken lines shown in the drawings illustrate portions of the scooter that form no part of the claimed design.
